UNITED STATES PATENT OFFICE.

CLEMENT E. GARDINER, OF HEMPSTEAD, NEW YORK.

DESIGN FOR A BONBON.

SPECIFICATION forming part of Design No. 23,691, dated October 16, 1894.

Application filed April 30, 1894. Serial No. 509,607. Term of patent 3½ years.

To all whom it may concern:

Be it known that I, CLEMENT EDWARD GARDINER, a subject of the Queen of Great Britain, residing at Hempstead, in the county of Queens and State of New York, have invented and produced a new and original Design for a Bonbon, of which the following is a specification, reference being had to the accompanying drawings, forming part hereof.

10 Figure 1 is a perspective plan view of my design. Fig. 2 is a cross sectional view taken on the line $x-x$ of Fig. 1, and Fig. 3 is an edge view, showing one of the tubes partly in longitudinal section.

15 The leading features of my design comprise a series of tubes a of different lengths laid side by side and connected together by webs d , the ends b of said tubes being open

and the ends c closed; the said tubes being contained within two parallel lines of unequal lengths, a line at right angles to said parallel lines, and a hypotenuse line. The rotundity of the tubes a , with the webs d provides corrugated upper and lower surfaces to the bon-bon, as seen in the drawings. 20 25

What I claim is—

The design for a bon-bon, substantially as shown and described.

In testimony that I claim the foregoing I have hereunto set my hand this 5th day of April, 1894. 30

C. E. GARDINER.
